UNITED STATES PATENT OFFICE

CLARENCE A. FORESMAN, OF CICERO, ILLINOIS; DAGNE ADELINA LUND ADMINISTRATRIX OF SAID CLARENCE A. FORESMAN, DECEASED

DESIGN FOR A FINGER-NAIL FILE

Application filed July 21, 1930. Serial No. 36,421. Term of patent 7 years.

To all whom it may concern:

Be it known that I, CLARENCE A. FORESMAN, a citizen of the United States, residing at Cicero, in the county of Cook and State of Illinois, have invented a new, original, and ornamental Design for Finger-Nail Files, of which the following is a specification, reference being had to the accompanying drawing, forming a part thereof.

Fig. 1 is a plan view of a finger-nail file showing my new design, and

Fig. 2 is a side elevational view thereof.

I claim:

The ornamental design for a finger-nail file substantially as shown.

CLARENCE A. FORESMAN.
